UNITED STATES PATENT OFFICE.

JOHN EDWARD MURPHY, OF WINNIPEG, MANITOBA, CANADA.

MECHANICAL STOKER.

1,140,761.

Specification of Letters Patent. Patented May 25, 1915.

Application filed March 10, 1914. Serial No. 823,731.

To all whom it may concern:

Be it known that I, JOHN EDWARD MURPHY, a subject of the King of Great Britain, and resident of 375 Notre Dame street, in the city of Winnipeg, Province of Manitoba, in the Dominion of Canada, have invented certain new and useful Improvements in Mechanical Stokers; and I do hereby declare that the following is a full, clear, and exact description of the same.

The invention relates to improvements in mechanical stokers as described in the present specification and illustrated in the accompanying drawings that form part of the same.

The invention consists essentially in the novel construction and arrangement of parts whereby the quantity of coal in the hopper leading to the feed opening of a furnace can readily be reduced to the minimum by the means employed for cutting off the main body of coal, and retaining same in hopper without danger of it burning.

The objects of the invention are to change the conditions existing quickly from a working fire to a banked fire and thus effect a great saving in fuel, to avoid unnecessary combustion of fuel in fire box and the cooling off of the boiler due to air entering through hopper and feed opening, to minimize the troubles incident of the burning back into the hopper from the firebox as is sometimes the case during feeding to a slow fire, and generally to provide a simple, efficient and durable stoker.

In the drawings, Figure 1 is a sectional perspective view showing the arrangement of the plates in the hopper mechanism. Fig. 2 is a cross sectional view of the stoker.

Like numerals of reference indicate corresponding parts in each figure.

1 are the side walls of the hopper extending to the furnace wall 2 and rigid therewith.

45 3 is a plate rigidly secured to the side walls 1 a short distance outwardly from the furnace wall 2 and terminating above the feed opening 5, said plate forming the inner wall of the hopper and spacing said hopper

50 from the furnace wall 2. This construction forms an air passage 6 behind the hopper through to the feed opening 5 besides providing a space which may also be used to introduce a poker to relieve any congestion 55 on the hopper chute.

7 are brackets secured to the walls 1 and

extending in a slanting direction downwardly to a point in alinement with the upper end of the feed opening 5.

8 is a cut off plate supported on the brackets 7 and extending upwardly beyond the walls 1 at the top end thereof and slidably arranged and supporting a great body of coal in the hopper under certain conditions.

9 are toothed racks rigidly secured to the under side of the cut off plate 8 at each end thereof.

10 is a shaft journaled in the side walls 1 toward the upper end thereof in that portion of said side walls most distant from the furnace, said shaft extending outwardly beyond one of said side walls 1 and having mounted thereon any suitable arrangement for operating, though the handle 11 is shown in the drawing, which operates the ratchet 12. This is common practice and is only merely mentioned herein.

13 are pinions rigidly mounted on the shaft 10 adjacent to the ends thereof and co-acting with the racks 9. Of course in the drawings only one pinion and one rack is shown, though the same construction is at the other end but is not illustrated.

It will be thus seen that by operating the handle 11 the cut off plate 8 may be raised and lowered as desired, and in raising said plate the upper part of said hopper will be put in communication with the lower part, while in lowering the plate the said plate is made the bottom of an upper compartment in the hopper for supporting the main quantity of coal. When the fire is banked this plate is lowered right to the furnace wall 2 stopping air from coming through passage 6 to the furnace and boiler thereby stopping unnecessary combustion of coal and cooling of boiler.

14 is a dead plate extending inwardly into the firebox from the sill 15, said sill 15 being at the lower end of the inclined plate 16.

17 is a pusher operated in any suitable way though here shown as slidable along the plate 16 over the sill 15 by the gear 18 operating the rack 19.

20 is an inclined plate having the lugs 21 encircling the shaft 10 and pivotally supporting said plate 20 from said shaft, said plate resting on the pusher 17 at its lower end and its upper end extending under the cut off plate 8, the said inclined plates 16 and 20 forming the chute bottom of the

hopper and over which the coal rolls into the feed opening 5.

In ordinary practice, and under steaming conditions, the cut off plate is raised so that 5 the great quantity of coal rests on the chute bottom and is continuously worked into the feed opening of the firebox by the operation of the pusher, but in this invention the upper portion of the hopper may be cut off 10 when it is desired to change conditions, and in place of banking the fire with a great quantity of coal or feeding it in by very small quantities, the fire is banked only by the coal which is left between the cut off 15 plate and the bottom of the hopper. This quantity is just sufficient for the purposes of a slow fire and consequently no more fuel is used than is actually required. Not only that but the condition of matters in 20 the furnace is such as to provide a temperature which will keep the boiler at a uniform degree without expenditure of quantities of fuel and therefore make the raising of the temperature of the water for steaming conditions much cheaper and simpler than under ordinary circumstances.

What I claim is:

1. In a mechanical stoker, a furnace wall having a feed opening therethrough, a hopper having side walls extending outwardly from said furnace wall, an inner wall secured to said side walls a short distance from said furnace wall and terminating above said feed opening and a chute bottom formed of 35 a rigid plate and a pivoted plate, a cut off plate extending across said hopper and beneath said inner wall to said furnace wall above the feed opening and slidably supported, and means for operating said cut off 40 plate.

2. In a mechanical stoker, an inner wall rigidly secured and terminating at its lower end above the feed opening to the firebox,

side walls rigid with said inner wall and extending outwardly therebeyond and projecting therebelow, a shaft journaled in the outer upper end portions of said side walls, pinions fixedly secured on said shaft, a cut off plate slidably supported by the side walls and extending downwardly from 50 above said shaft beneath the lower end of said inner wall, toothed racks on said cut off plate co-acting with said pinions, a plate pivotally supported from said shaft and extending downwardly therefrom below said 55 cut off plate, and a rigid inclined plate extending to said feed opening under said pivoted inclined plate.

3. In a mechanical stoker, an inner wall rigidly secured to and spaced from the furnace wall above the feed opening to the firebox, side walls standing out beyond said inner wall and rigid therewith, a shaft journaled in the outer upper ends of said side walls, a plate slidably supported from said 60 side walls and extending downwardly from above said shaft under the lower end of said inner wall, means operatively connecting said plate and said shaft, a permanent inclined plate extending upwardly 70 from the lower end of said feed opening, a pusher suitably operated over said inclined plate, an upper inclined plate having lugs extending therefrom pivotally supporting said plate from said shaft under 75 the aforesaid plate, said upper inclined plate at its lower end resting on the upper side of said pusher, and means for operating said shaft.

Signed at city of Winnipeg, Province of 80 Manitoba, Dominion of Canada, this twenty-ninth day of January, 1914.

JOHN EDWARD MURPHY.
